[57] CLAIM

The ornamental design for vacuum bottle, as shown and
described.

DESCRIPTION

FIG. 1 is a perspective view of a vacuum bottle showing
our new design;

FIG. 2 is a front elevational view thereof;

FIG. 3 is a top plan view thereof;

FIG. 4 is a bottom plan view thereof.

A rear, a left side and a right side elevational views are
identical with the front elevational view.

FIG. 1

FIG. 2

FIG. 3

FIG. 4
